United States Patent Office

Des. 196,690
Patented Oct. 22, 1963

196,690
WARNING LIGHT

Lyle D. Atkins, 655 Olmos Drive, and Chester M. Norton,
446 Pilgrim, both of San Antonio, Tex.

Filed Aug. 20, 1962, Ser. No. 71,367

Term of patent 14 years

(Cl. D72—1)

FIG. 1 is an isometric view of a warning light, showing our new design; and

FIG. 2 is another isometric view thereof.

The undisclosed sides are substantially the same in appearance as the sides shown.

We claim:

The ornamental design for a warning light, substantially as shown and described.
